Howard M. Cohn(57) **CLAIM**

The ornamental design for a suction cup hook, as shown and described.

DESCRIPTION

FIG. 1 is a top perspective view of a suction cup hook showing my new design;

FIG. 2 is a bottom perspective view thereof;

FIG. 3 is a front elevational view thereof; the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof; and,

FIG. 8 is a top perspective view of the suction cup hook in another configuration.
